UNITED STATES PATENT OFFICE.

RALPH L. LEE, OF DAYTON, OHIO.

TOY BALL.

Application filed January 21, 1921. Serial No. 438,878.

This invention relates to devices of the class adapted to revolve or roll under their own power, and more particularly that type which roll on floors or other surfaces.

5 My invention is peculiarly adapted for use as a toy, and it is an object of this invention to provide a toy ball having in its interior a spring motor which will cause the ball to roll along the floor without any assistance from sources exterior to the ball.

10 Further objects and advantages of the present invention will be apparent to those skilled in the art from the following description, reference being had to the accompanying drawings, wherein a preferred embodiment of the invention is clearly shown, and wherein:

Fig. 1 is a vertical section of the invention on line 1—1 of Fig. 2;

20 Fig. 2 is an irregular vertical section on the line 2—2 of Fig. 1, certain of the parts being shown in elevation to more clearly illustrate the relation of the parts;

25 Fig. 3 shows in perspective certain details of construction; and

30 Figs. 4 and 5 are diagrams illustrating the operation of the invention.

Referring to the drawings, the ball consists of a hollow member or casing 10, and a 35 spring motor 20 pivotally suspended from the center thereof. The casing consists of two sections 11 and 12 fitted together in the manner shown or in any other preferred manner to form a hollow casing of any desired shape. Rigidly secured to the interior of the casing 10 and in alignment with one another are hollow supporting studs 13 and 14, which have aligned bores 15 constituting 40 bearings for the reduced ends or spindles 16 of main shaft 17. Keyed or otherwise secured to the end of stud 13 is a gear 18, the purpose of which will be described later. The casing is herein shown as spherical in shape, and the supporting studs on a line 45 passing through the center of the sphere, but it will be understood that the casing may assume in transverse cross section any shape suitable for rolling or tumbling, whether it be circular, oval, oblate, or polygonal and 50 that the longitudinal cross section may assume any shape which will facilitate rolling or tumbling in a straight line or in any irregular course, and that the supporting studs need not be located at the center of 55 the casing as herein shown.

The spring motor 20 has a frame made

up of side plates 21 and 22 and studs 23 for rigidly holding the plates in spaced relation to one another. As shown in Fig. 2, the plates 21 and 22 are pivotally supported 60 on the spindles 16, and in fact, the entire weight of the motor is carried by spindles 16. The entire motor, including the main shaft 17 and spindles 16, is adapted to rotate in the bearings 15, the only driving 65 connection between the motor and the hollow casing being that obtained by the engagement of gear 29 with gear 18 rigidly secured to the stud 13. The purpose of this engagement will be later explained. Referring to Figs. 1 and 3, the main spring 33 of the motor is attached at its inner end by means of a pin or other preferred connection to the main shaft 17 and at its outer end to one of the studs 23, as shown. Adjacent to the main spring 33 and revolvably mounted on the shaft 17 is a gear 24 which has engagement by means of the pawl 25 with the ratchet wheel 26 secured to the main shaft 17. The gear 24 drives the gear 70 train 27, 28, and 29, the gear 29 being in engagement with the gear 18 rigidly secured to the supporting stud 13 as previously explained. The speed of the train is regulated by the escapement mechanism 30 which 75 is driven from gear 28 through the pinion 80 31.

Referring to Figs. 2 and 3, it will be seen that the section 12 of the casing is provided with an opening in alignment with the hollow stud 14 whereby a key 32 may be inserted to wind the main spring. In the embodiment of the invention illustrated, the main spring is wound by turning the key to the right as indicated by the arrow in Fig. 90 3 and when this is done the ratchet wheel 26 moves under the pawl 25, the escapement mechanism 30 effectively holding the spring motor against unwinding, in a manner to be hereinafter more fully described. After the 95 spring is wound, the energy of the spring is transmitted through the shaft 17 to the ratchet wheel 26 which exerts a force on the gear 24 to drive it in the direction indicated by the arrow in Fig. 1. Gear 24, operating 100 through the train 27 and 28, causes gear 29 to rotate in the direction indicated in Fig. 1. Since the gear 18 is fixed on the stud 13 the gear 29 must travel around the gear 18 in a 105 clockwise direction, thus swinging the entire spring motor to the left about the spindles 16 as a center, as viewed in Fig. 1.

The operation of this device will be better understood by reference to the diagrammatic views shown in Figs. 4 and 5. In Fig. 4 the ball is shown at rest and in equilibrium 5 on the plane surface A—B, the point of support being indicated at P. With a spherical ball in stable equilibrium, as shown, the center of gravity of the hollow casing 10 is at its center, spindle 16, and the center of 10 gravity of the spring motor is of course at a point directly underneath, as at M. Since the weight of the ball is made up of the weights of the hollow casing 10 and the motor 20, its center of gravity is on the line 15 connecting their respective centers of gravity, 16 and M, and is located between them, as at G. As is well known, the center of gravity of any object is the point at which the entire weight of the object may be assumed to be concentrated. In the present case, the weight of the ball will be assumed to be concentrated at the point G. The downward pressure caused by the weight of the ball is represented by the heavy arrow 20 through the center of gravity G. In Fig. 4 it is in line with and directly opposed to the upward pressure through the point of support P, which means that the ball is in stable equilibrium and there is no tendency 25 to roll. But when the motor is put into operation, the first effect is to swing the center of gravity out of the line of support O—P to a point, as for instance G', shown 30 in Fig. 5. The ball is thereby placed in unstable equilibrium, the upward force through P and the downward force through G' constituting a couple tending to roll the ball in the forward direction about the point of support P as indicated by the arrow F in 35 Fig. 5. When the center of gravity returns to G in the line of support O—P, the ball is once more in stable equilibrium. With continued operation of the motor the center 40 of gravity is again moved to the left of the line of support O—P, the distance of the point G' from the line of support O—P at any instant depending upon the resistance offered to the rolling of the ball. Should the ball come in contact with a small obstacle, as Q shown in Fig. 5, the spring motor 45 will continue moving the center of gravity G' out to the left to a point more remote from the line of support O—P until the resistance of the obstacle is overcome and the ball rolls over the obstacle. Should the center of gravity G' move to its extreme position most remote from the line O—P, and the ball still not roll, as when it meets a large immovable obstacle or a wall, the 50 motor will nevertheless continue to move the center of gravity about 16 in a clockwise direction to a point G² on the line of support O—P. The ball is now in unstable equilibrium and any further movement of 55 the motor will carry the center of gravity

G² to the right of O—P and cause the ball to roll away from the wall in a backward direction as indicated by arrow B in Fig. 5, the motor all the while continuing to operate in the manner already explained. After 70 the center of gravity returns to the point G the ball will, of course, again continue its forward movement in the direction F indicated in Fig. 5, though as the ball falls over it will probably turn as it falls and 75 continue its forward movement in a direction different from the direction it pursued before it came in contact with the wall. It will be understood that the ball does not depend entirely on the operation as above outlined for its ability to overcome obstacles, but that it will be greatly assisted by its own inertia of motion as it rolls forward. 80

As already stated, the escapement 30, in addition to its normal and customary function of regulating the speed of the motor in unwinding, also serves as a lock to hold the motor against operation while it is being wound by the key 32. This double function is rendered possible, in the form of the invention herein illustrated, by interposing an idler gear 29 in the gear train. Referring to Fig. 1, it will be observed that as the winding shaft 17 and the ratchet wheel 26 are turned in a counter-clockwise direction 90 in winding and the spring 33 is placed under tension, such spring tension immediately manifests itself at the outer end of the spring by a tendency to rotate the side plates and motor mechanism in a counter-clockwise direction about the reduced ends 16 of the shaft 17. However, any such rotation would cause a rotation of the gears 29 and 28 in a direction reverse to the arrows but this is prevented by the escapement 30 as will be 95 readily understood by those skilled in the art. 100

The construction described has the peculiar advantage that the entire winding operation may be performed by simply oscillating the winding key back and forth without changing the grip of the hands on either the ball or the winding key. During the forward or winding motion of the winding key 32 the motor is held against rotation in 110 the ball, as already described, and the ratchet 26 moves under the pawl 25 in a counter-clockwise direction as viewed in Fig. 1. On the backward motion of the winding key 32, the motor unwinds within the ball, the motor 115 frame and the pawl and ratchet, with the winding key attached, moving in a clockwise direction (Figs. 1 and 5), and the ball or casing 10 moving in a counter-clockwise direction. During the backward motion of the winding key, the motor of course gives up some of its tension but this is a small fraction of the tension or energy which was given to it on the preceding forward motion 120 of the winding key, the net result being 125 130

that with each back and forth oscillation of the key the spring tension is increased and the spring motor is wound up more quickly and conveniently than if a new grip had to be taken after each forward motion of the winding key.

My invention is herein shown and described as applied to a ball supported at a point P, and its operation explained with reference to the vertical line passing through the point of support which has been termed the line of support O—P. It will be understood that with a rolling or tumbling casing of different transverse cross sectional form than that shown or of different longitudinal cross section, the support may be a line instead of a point, or even a surface. In case the support is a surface, it will be understood, of course, that the ball will not be in unstable equilibrium unless its center of gravity falls outside of the supporting area. With respect to motion of the ball, as described with reference to Fig. 5, the so-called line of support beyond which the center of gravity must pass before the ball is in unstable equilibrium, must be considered to be the vertical line passing through the edge of the supporting area most advanced in the direction of travel, and where the term "line of support" is employed in the claims it is intended to have this interpretation.

While I have shown one preferred embodiment of one form of my invention, it will be understood that various changes and alterations in its form, proportions, details of construction and arrangement of parts may be made without departing from the spirit and scope of the invention.

What I claim is as follows:

1. A motor propelled toy comprising a supporting means, an overturnable motor pivotally mounted on the supporting means and having a driving connection therewith, and means including a winding shaft coaxial with the pivotal axis of said motor for winding the motor, said motor carrying provisions associated with said driving connection for holding the motor against rotation about its axis during application of the winding force.

2. A motor propelled toy comprising a supporting means, an overturnable motor pivotally mounted on the supporting means and having a driving connection therewith, and means including a winding shaft coaxial with the pivotal axis of said motor for winding the motor, said motor including an idler gear in said driving connection and an escapement mechanism associated with

the driving connection for holding the motor against rotation relative to its axis during application of the winding force.

3. A motor propelled toy comprising a support, an overturnable motor pivotally mounted on the support, a driving connection from the motor to the support adjacent the pivotal axis of the motor, and means including a winding shaft coaxial with the pivotal axis of the motor for winding the motor, said driving connection including a gear train of an uneven number of driving and driven surfaces carried by the motor and the support, and means associated with the gear train for preventing movement of the gears in one direction whereby to hold the motor against rotation about its axis during application of the winding force.

4. A motor propelled toy comprising, a supporting member adapted to roll on a supporting surface, an overturnable spring motor rotatably mounted on said supporting member and having a driving connection therewith tending to cause rolling of said supporting member, and means including a winding shaft coaxial with the axis of rotation of the spring motor for winding the spring motor, said spring motor carrying means for holding the motor against unwinding during application of the winding force.

5. A motor propelled toy comprising a supporting means, an overturnable spring motor rotatably mounted on the supporting means and having a driving connection therewith, means for winding said motor, and means permanently associated with the motor and operable automatically upon winding of the motor for holding the motor against rotation about its axis during application of the winding force.

6. A motor propelled toy, comprising a support, an overturnable motor having a motor frame, a main shaft coaxial with the axis of rotation of the motor, a main spring secured at one end to said motor frame and at its other end to said main shaft, a driving connection between said shaft and said support whereby rotation of said shaft in a given direction under tension of said spring will cause rotation of the motor relative to the support, and means forming a unitary part of said device coacting with the motor upon rotation of said shaft in an opposite direction to restrain movement of the frame in said opposite direction.

In testimony whereof I hereto affix my signature.

RALPH L. LEE.
